UNITED STATES PATENT OFFICE

JOHN AUGUST HOLMBERG, OF LINDSBORG, KANSAS

STEAM-RADIATOR RETURN VALVE

Application filed September 27, 1928. Serial No. 308,759.

The invention relates to return valves for the radiators of steam heating systems, and it aims to provide a new and improved construction which will act automatically to permit escape of all air, will then act to trap the steam, and at proper intervals will permit discharge of the water of condensation.

A further aim is to provide a new and improved valve which will act as an equalizer, causing equal distribution of steam to all radiators; will equalize the pressure in the steam and return lines, enabling the condensation to flow freely back to the boiler without the use of a pumping device; will be self-cleaning, as there are no places in which sediment and scale may lodge, allowing them to wash down through the return line; will permit blowing out of the entire system whenever advisable; may be easily inspected from time to time; may have its movable parts quickly and easily removed for repair or replacement, and reinserted with equal speed and ease.

With the foregoing in view, the invention resides in the novel subject matter hereinafter described and claimed, description being accomplished by reference to the accompanying drawing.

Fig. 1 is a vertical sectional view of the improved valve in condition for exhausting air from a radiator.

Fig. 2 is a view similar to Fig. 1 but showing the manner in which the valve opens to permit the condensation to discharge.

Fig. 3 is a vertical sectional view on line 3-3 of Fig. 1.

The drawing above briefly described illustrates the preferred form of construction and while such construction will be herein specifically explained, it is to be understood that within the scope of the invention as claimed, variations may be made.

The valve embodies a cylindrical casing 5 having an inlet 6 in one of its vertical end walls 7, the other end wall 8 being threaded in place or otherwise secured for easy removal. At the bottom of the casing 5, is an outlet 9. This outlet is adapted for connection with the return line of the heating system, and the inlet 6 is of course connected to

the outlet of the radiator, an appropriate connection 10 being shown for this purpose.

The inner end of the inlet 6 is flared or otherwise increased in size as shown at 11, and around this enlarged inner end is a valve seat 12 which is formed integrally with the casing end 7, in the present disclosure. A flap valve 13 is pivotally hung in the casing 5 for co-operation with the valve seat 12. This flap valve is in the form of a substantially diamond-shaped plate 13 having an integral tongue 14 at its upper end. This tongue is bent to form a hinge knuckle 15, is then extended laterally to provide one arm 16 of a yoke, is then bent downwardly to form a body portion 17 of the yoke and is finally bent inwardly and downwardly at 18, providing the other yoke arm, which arm is riveted or otherwise secured at 19 to the lower end of the plate 13. Interposed between the yoke body 17 and the plate 13, is a wafer-type thermostat 20 secured by appropriate means 21-22, to said yoke body 17. This thermostat carries a valve 23 which, under circumstances hereinafter described, closes an air port 24 which is formed through the plate 13.

A resilient frame is provided within the casing 5 and is preferably in the form of a transversely split, self-expanding, spring metal ring 25 having an inwardly offset portion 26 around which the hinge knuckle 15 passes to pivotally support the flap valve 13 and the parts carried thereby. Around the inner side of the peripheral wall of the casing 5, is a groove 27 in which the ring 25 is snapped, the ring being thus held properly in place by its own resiliency and serving to effectively support the valve unit. This construction also permits rotary adjustment of this valve unit when it is initially installed, so that it will hang freely with its pivotal support directly in vertical alignment with its center of mass. Removal of the casing end 8 permits springs of the ring 25 from the groove 27, allowing the entire valve unit to be removed for cleaning, repairing or replacement, and either the old repaired unit or the replacement unit may be inserted with equal speed and ease.

When the valve is connected with the radi-

ator and return line and the steam is admitted to the radiator, air is driven from the latter through the air port 24 into the casing 5 and on through the return line from which it is disposed of by the usual air eliminator. During this discharge of air, the valve 23 is of course open and the flap valve 13 is closed, as seen in Fig. 1. As soon as the air has been exhausted and steam reaches the inlet 6, it acts upon the thermostat 20 and closes the valve 23, so that no leakage of steam can take place. The pressure of the steam is insufficient to cause opening of the flap valve 13, but as soon as a sufficient quantity of water of condensation has collected, the outward force of this water due to its weight, causes opening of the valve 13 as seen in Fig. 2, permitting the water to drain into the casing 5 and pass from the latter to the return line. In connection with this travel of condensation, it may be explained that the inner end 11 of the inlet 6 is enlarged to expose a greater surface of the valve 13 to the water accumulating in the inlet and also to provide a construction in which there is no liability of any sediment or scale lodging, said construction being such that any foreign matter which is held in check by the valve 13 while the latter is closed, will immediately wash out upon opening of said valve. If the inlet 6 were not enlarged at 11 over the internal diameter of the pipe connection, sufficient weight of water could not accumulate directly in said inlet to open the valve 13, but would have to back up to some extent in the radiator to attain this end. Then too, there would be much more danger of scale and sediment lodging in the inlet.

In other heating systems, using what is called a thermostatic trap on the radiator, both the air and condensation must pass through a small opening, and when all of the radiators are hot, all of the thermostats have tightly closed until enough condensation has accumulated in the radiators to cool the thermostats and permit slight opening thereof for passage of condensation. This method holds some water away from the boiler. It also creates a lower pressure in the return line than in the steam line and boiler. Consequently, some kind of pumping device is necessary to return the condensation to the boiler and keep the returns from getting water-logged. Furthermore, this type of system cannot be blown out clean even if the thermostats are removed, as the openings controlled by these thermostats are of insufficient size. With the present valve, however, the flap will always open sufficiently to keep approximately the same pressure in the return and the steam lines, allowing the condensation to run freely back to the boiler without the use of a pump. Then too, when the system is cleaned by blowing it out, the flap valves of the various radiators will open and provide large free passages through which

scale and the like may pass. This alone is quite an advantageous feature, as heating systems will accumulate a great deal of sediment and scale and if such systems are not occasionally cleaned will become sluggish and inefficient. 70

On account of the excellent results obtainable from the details disclosed, they are preferably followed as above stated. However, attention is again invited to the fact that within the scope of the invention as claimed, variations may be made. 75

I claim: —

1. A steam radiator return valve comprising a casing having an inlet in one wall and a constantly open outlet at its bottom, a self-closing water-opened valve mounted in said casing for closing said inlet to prevent entrance of steam into the casing from the radiator, said valve being inwardly movable to open position under the pressure of water of condensation reaching said inlet from the radiator, said valve being formed with an air port registering with said inlet to permit entrance of air prior to arrival of steam at said inlet, an air valve for closing said port, and a steam-operated thermostat for closing said air valve, both said air valve and said thermostat being mounted in their entirety upon the said self-closing water-opened valve, whereby this valve is unaffected by the action of said thermostat. 80

2. A structure as specified in claim 1; said wall being vertical and formed with an annular valve seat around said inlet co-operable with said self-closing water-opened valve, the inner end of said inlet being flared to expose more area of said self-closing water-opened valve to the water and to provide a formation in which sediment will not lodge. 90

3. A steam radiator return valve comprising a casing having an inlet in one vertical wall and a constantly open outlet at its bottom, a self-closing water-opened flap valve pivotally hung in said casing for closing said inlet to prevent entrance of steam into the casing from the radiator, said flap valve being inwardly swingable to open position under the pressure of water of condensation reaching said inlet from the radiator, said flap valve being formed with an air port registering with said inlet to permit entrance of air into the casing prior to arrival of steam at said inlet, an air valve for closing said port, and a steam-operated thermostat for closing said air valve, both said air valve and said thermostat being mounted in their entirety upon said flap valve. 100

4. A steam radiator return valve comprising a casing having an inlet in a vertical wall and a valve seat on said wall around said inlet, a flat valve plate co-operable with said seat and having an air port registering with said inlet, means pivotally hanging said valve plate for movement toward and from said 110

seat, a yoke having its arms secured to said plate, the arm-connecting portion of said yoke being inwardly spaced from said plate, a wafer-type thermostat between said valve plate and said arm-connecting portion of said yoke and secured to the latter, and an air valve carried by said thermostat and closable against the inner side of said valve plate, the lower side of said casing being provided with a constantly open outlet.

10 5. In a valve, a casing, a spring metal frame within said casing and held in contact therewith by its own resiliency, and a valve member mounted in its entirety upon said frame.

15 6. In a valve, a cylindrical casing having an internal groove in its continuous wall, a transversely split spring metal ring snapped removably in said groove, and a valve member mounted in its entirety upon said ring.

20 7. In a valve, a cylindrical casing, a transversely split spring metal ring contacting with the inner side of the continuous side wall of said casing and held against the same by its own resiliency, said ring having an inwardly offset portion, a hinge knuckle surrounding said off-set portion, and a valve member carried by said knuckle.

25 8. In a valve, a spring-metal self-expansible frame, for reception in a casing to be held therein by its own resiliency, and a valve member carried by said frame.

30 9. In a valve, a transversely split self-expapsible spring metal ring for reception in a casing to be held therein by its own resiliency, said ring having an inwardly offset portion, a hinge knuckle surrounding said offset portion, and a valve member carried by said knuckle.

35 40 10. In a valve, a valve plate having an opening an elongated tongue integral with the edge of said plate said tongue being bent to form a hinge knuckle for the plate and further bent to provide a yoke, the body portion of the latter being spaced from said plate, means securing the free end of said tongue to said plate, a thermostat carried by said yoke, and a valve on said thermostat co-operable with said opening.

45 50 50 In testimony whereof I have hereunto affixed my signature.

JOHN AUGUST HOLMBERG.
